UNITED STATES PATENT OFFICE.

LAURENCE M. FOSS, OF AMESBURY, MASSACHUSETTS, ASSIGNOR TO G. W. J. MURPHY COMPANY, OF AMESBURY, MASSACHUSETTS, A CORPORATION OF MASSACHUSETTS.

SECURING MEANS FOR FASTENER ELEMENTS.

Application filed November 19, 1921. Serial No. 516,456.

To all whom it may concern:

Be it known that I, LAURENCE MELVIN Foss, a citizen of the United States, and a resident of Amesbury, county of Essex, and State of Massachusetts, have invented an Improvement in Securing Means for Fastener Elements, of which the following description, in connection with the accompanying drawings, is a specification, like characters on the drawings representing like parts.

This invention relates to a means for securing such devices as the elements of separable fasteners which are mounted on a supporting member such as a curtain or the like by parts adapted to be riveted or bent over on the supporting member. The object is more particularly to provide a secure device of this kind which may be easily and quickly applied and which will insure a neat piece of work and one which when finished will be of seemly appearance.

As a specific example of my invention I have shown an embodiment thereof as applied to the eyelet or grommet of a turnbutton fastener and this specific embodiment of my invention will be readily understood by reference to the following description taken in connection with the drawing, wherein:

Fig. 1 is a central vertical section through an eyelet and the cooperating securing means showing the associated turnbutton in elevation;

Fig. 2 is a section on the line 2—2 of Fig. 1;

Fig. 3 is part side elevation part section on a reduced scale of a setting tool for setting the parts shown in Figs. 1 and 2;

Fig. 4 is an end view thereof as seen from the right of Fig. 3; and

Fig. 5 is a section on the line 5—5 of Fig. 3.

Referring to the drawing, I show in Fig. 1 a turnbutton 7 which may be of the type shown in my Patent 1,201,682 of October 17, 1916, which is adapted to hold the curtain 9 by cooperation with the elliptical eyelet or grommet 11 carried by the curtain. The outer flange of the eyelet is provided with a series of prongs 13 adapted to pass through the curtain and be upset on the rear side thereof. The eyelet with these prongs as here disclosed constitutes an example of a fastener element which is secured to a supporting member, such as the

curtain 9, by means of a part adapted to extend through such a member and be bent down or riveted over thereon. It will be understood that while one particular form of such an element is herein shown by way of illustration the invention is applicable to devices of different type.

I here show the prongs 13 as upset over a washer 15 (see Fig. 2) which may be of comparatively strong and durable metal such as steel and the washer may be of undulated form and embody portions 17 adapted to lie against the back of the curtain and over which the prongs 13 are bent and relatively offset portions 19 alternating with the portions 17. To provide a neat finish I utilize a dished cover plate 21 which is preferably of more seemly metal than the washer. For example, it may be made of thin brass. This cover plate overlies the back and outer margin of the washer, covers the same and provides a smooth finish for the completed job at the rear of the curtain. The cover plate 21 is secured to the washer 15 and I have herein shown tabs 23 around the inner periphery of the cover plate clenched on the offset portions 19 of the washer which lie against the inner surface of the cover plate.

It will be understood that the prongs 13, when the parts are being assembled, extend out substantially perpendicular to the front face of the eyelet 11. The cover plate 21 is preferably formed to present to the prongs of the eyelet 11 surfaces adapted to upset the prongs and bend them over on the washer 15. The cover plate for this purpose may be backed up by a suitable tool during the setting operation. It will be noted that the portions 17 of the washer 15 define with the cover plate pockets (see Fig. 1) into which the prongs are adapted to be clenched, they being bent over therein by the action of the inner surface of the plate 21 opposing them.

To provide greater security in the fastening, parts 25 of the portions 17 of the washer adjacent where the prongs enter are bent rearwardly at a slope or bevel so that the margins lie adjacent the upsetting surfaces of the cover plate 21. The prong is thus clenched closely over the edge of the washer and the eyelet securely held even if the end of the prong is not reversely bent into contact with the portions 17 which lie against the rear face of the curtain and in most in-

stances a two point support is provided for the upset prong. The rearward bending of the parts 25 provides a flaring mouth 27 between the washer and the adjacent casing 21 which facilitates the introduction of the prongs thereto, contributes to a proper alignment of the eyelet and the securing device and guides the prongs accurately towards the upsetting surfaces of the back plate 21.

In Figs. 3, 4 and 5 I have illustrated a suitable tool for setting the eyelet as disclosed in Figs. 1 and 2. The tool may comprise a stock 31 on which is mounted the 15 clenching portion 33 having the annular recess 35 adapted to receive the backing plate 21 and to fit and support the same during the clenching operation so that the backing plate although of thin metal will be effective to upset the prongs 13. In the tool shown I also provide the centrally mounted pilot 37 adapted to extend through and fit the opening in the backing plate 21 and the washer 15 through which the base of 25 the turnbutton 7 extends in the manner shown in Fig. 1. This pilot member is supported in the stock by the spring 39 to permit the same to yield inwardly so that the clenching may be effected.

I herein provide means for retaining the securing member temporarily on the pilot to hold it in place against the surface 35, thus facilitating the operation of assembling it with the eyelet 11. I have herein shown a spring wire 40 secured across the end of the pilot and having curved arms 41 projecting from the sides of the pilot in axial planes and forming spring catches. Referring to Fig. 3, it will be seen that 40 the annular securing device may be slipped over the end of the pilot and, following the curve of the arms 41, will pass over the high points thereof which will snap out beneath it and the spring arms will hold the 45 securing device against the surface 35. Then when the pilot is inserted in the central opening of the eyelet 11, the securing device will be automatically aligned with the eyelet. The pilot is preferably cut away at 50 43 to provide an open space into which the free ends of the spring arms 41 extend and the inner periphery of the annular surface 35 will, as the pilot is pressed inwardly in

the clenching operation, act on the springs and bend them inwardly. When the clenching is finished, the high points on the spring arms 41 will lie above the back plate 21 and the tool is removed from the completed work without any resistance from the springs 41 which are thus automatically disengaged from the securing member as an incident to the clenching operation.

Having thus described in detail the particular embodiment of my invention shown by way of example in the accompanying drawing, what I claim as new and desire to secure by Letters Patent I shall express in the following claims:

1. A securing means for cooperation with a fastener element which has a plurality of prongs to extend through a supporting member comprising an undulated washer providing relatively depressed and raised portions and a cover plate secured to said raised portions and defining with said depressed portions prong receiving pockets and presenting an upsetting surface to clench the prongs into said pockets.

2. A securing means as defined in claim 1 wherein the margins of said depressed portions are rearwardly bent.

3. A securing means for cooperation with a fastener element which has a plurality of prongs to extend through a supporting member comprising a washer, a cover plate closely fitting the margin of said washer but defining therewith a peripheral series of prong receiving openings, said plate presenting an upsetting surface to clench prongs projected through said openings over the washer.

4. A securing means for cooperation with a fastener element which has a plurality of prongs to extend through a supporting member comprising a washer, a cover plate closely fitting the margin of said washer but defining therewith a peripheral series of prong receiving openings, the margins of the washer at said openings being rearwardly bent, said plate presenting an upsetting surface to clench prongs projected through said openings over the washer.

In testimony whereof, I have signed my name to this specification.

LAURENCE M. FOSS.
